**PORTABLE COLLAPSIBLE BACKSTOP FOR
BASEBALL PRACTICE**

Lawrence W. Hubrich, 608 Lafayette St., Griffith, Ind.
Filed Apr. 8, 1963, Ser. No. 271,248
7 Claims. (Cl. 273—26)

This invention is primarily designed to fill the urgent need of managers and coaches of boy baseball teams who find their practices curtailed by the lack of back stopped playing fields.

One of the principal objects of this backstop is to provide a device which will immediately convert any field or playground of adequate size into a practice field. Conventional backstops for baseball use are generally constructed of heavy wire screen secured to posts of wood or metal and anchored permanently in the playing field. Such backstops are necessarily expensive to construct, and once constructed limit the use of the field because the permanency of construction hinders the free use of the field. The point to be emphasized here is that this invention instantly converts any field, even a pasture where it is hardly conceivable that a permanent backstop of conventional construction would be practicable, into a practice field.

A further object of this invention is to provide a readily portable backstop wherein the entire assemblage is light in weight, easily erected and collapsible, and capable of easy handling by one man. In the collapsed state this device has a circumference of less than 24 inches and is readily transportable in any automobile trunk or even under one's arm.

In view of the compactness of the collapsed structure of this device it creates no storage problem. The folded net and collapsed backstop has a minimum circumference and may be placed in any corner or small closet.

A further object of this invention is to provide an easily erected and collapsible backstop which can be erected and/or collapsed in 15 seconds by the movement of a single operating lever, placement or removal of the bipod, and mounting or dismounting of the corded net.

A further object of this invention is to provide the safety of a backstop with a corded net which absorbs the impact of the ball thus eliminating recoil or bounce back into the receiver, batter or other player in the immediate proximity of the net.

A feature of this invention relates to a novel backstop device operated on the principle of an inverted umbrella thus facilitating its easy erection and collapsibility by the operation of a single lever.

Not being exposed to weather the year around as are all stationary or permanent backstops this device will give unlimited service.

With this device it is possible to give individual attention to boys with isolated problems, without monopolizing the entire field and the standard large fixed backstop located thereon. The regular squad practice may proceed unhampered while a coach may take aside one or more boys, quickly erecting our portable backstop and giving them undivided attention with their individual problems.

This feature makes our device especially useful to high school or college coaches handling large squads.

A further object of this invention is to provide readily available backstops for picnic groups, boy scout camps and outings.

FIGURE 1 depicts the complete backstop in operational position viewed from the rear, suspending heavy nylon corded net from four arms.

FIGURE 2 is a view thru section of the operating apparatus.

FIGURE 3 shows the back stop much as it is in FIG-

2

URE 1 except that it is a front view, with cut-away view of front assembly in open position.

FIGURE 4 is a drawing of the curved extremity of the suspending arm showing manner of net attachment via hook.

FIGURE 5 shows the backstop in complete collapsed position.

FIGURE 6 is a detail drawing showing how the bipod is attached.

10 Referring to FIGURES 1, 2, 3 and 5, a piston 4 is inserted within a cylinder 5. These parts are preferably of circular cross section. Support arms 2 are attached to the end of the cylinder 2. Arm braces 3 are attached at one end to the support arms 2 and at the other end to the piston 4. An operating lever 7 has one end attached to the piston 4. A toggle lever 6 is attached at one end to the piston 4 and the other end to the operating lever 6. The support arms 2, arm braces 3, and levers 6 and 7 are attached to each other and to the cylinder and piston by hinges 10 as shown.

15 In FIGURE 1 the detachable bipod support 8 is shown. The bipod is attached to main assembly by means of an insert hook which enters into an appropriate opening in the cylinder end.

20 FIGURE 5 must be constructed of lightweight pipe or channel iron of sufficient tensile strength to afford adequate support.

25 The arms 2 as in FIGURES 1, 2, 3, 4 and 5 must also be made of lightweight pipe or channel iron of sufficient strength to support net and give lasting service.

30 *Operation.*—Opening or collapsing the backstop is performed basically by the simple movement of the operating lever 6. In the closed or collapsed position the operating lever lies forward parallel with the support arms 2. The arms 2 are all drawn closely together in cluster approximately 24 inches in circumference.

35 To erect or open pull back on operating lever 6. This action causes the piston 4 to be drawn back into the cylinder 5 simultaneously opening or spreading the arms 2, until the operating lever 6 lies back in a locked position parallel with and resting upon top surface of cylinder 5 and the arms 2 spread wide to the full open position, FIGURES 1 and 3. The net is then hooked into the net hooks 9 which are attached to the curved ends of the suspending arms 2 as in FIGURE 1. The final detail is to attach the bipod 8 by inserting the curved insert finger at the apex of bipod 8 into the round opening in the end of the cylinder 5 thus completing the erection, FIGURES 1 and 3. The simplicity of operation is such that one man can perform the cycle in 15 seconds. To take down or collapse proceed in reverse order 3-2-1.

40 While I have shown and described specific embodiments of the present invention, it will of course be evident that many and various modifications and alternative constructions may be made without departing from the true spirit and scope thereof. Thus, I intend by the appended claims to cover all such modifications and alternative constructions as come within their true spirit and scope.

45 I claim:

50 1. A portable collapsible backstop device comprising a hollow cylinder, a piston having a part adapted for movement within the cylinder, a plurality of support arms and means hinging them to the cylinder, a plurality of arm braces and means hinging each at one end to the piston and at the other end to one of the support arms, an operating lever and means hinging it to the cylinder, a toggle lever and means hinging it at one end to the operating lever and at the other end to the piston; so constructed and arranged that the operating lever is 55 adapted for manual operation to move the toggle lever which moves the piston within the cylinder, which in turn moves the arm braces and support arms

between a closed position and an open erect position;

the closed position being with said part of the piston generally extended from the cylinder and the support arms projecting in a cluster near the axial line of the piston and cylinder with the outer ends of the support arms beyond the cylinder in the same direction as the piston extends;

the erected position being with said part of the piston drawn into the cylinder and the support arms spread wide, with the plane formed by the outer ends of the support arms being beyond the forward end of the piston;

support means attached in the erected position to the rear end of the cylinder;

and a ball-stopping member comprising a corded net which is attached by loops located on the peripheral winding of the net to net hooks on said outer ends of said support arms.

2. A backstop device according to claim 1, wherein said operating lever in the closed position lies forward along the piston, and in the erected position lies back along the cylinder, being moved substantially 180° in operation from one position to the other.

3. A portable collapsible backstop device comprising a hollow cylinder, a piston having a part adapted for movement within the cylinder, a plurality of support arms and means hinging them to the cylinder, a plurality of arm braces and means hinging each at one end to the piston and at the other end to one of the support arms, an operating lever and means hinging it to the cylinder, a toggle lever and means hinging it at one end to the operating lever and at the other end to the piston;

so constructed and arranged that the operating lever is adapted for manual operation to move the toggle lever which moves the piston within the cylinder, which in turn moves the arm braces and support arms between a closed position and an open erect position;

the closed position being with said part of the piston generally extended from the cylinder and the support arms projecting in a cluster near the axial line of the piston and cylinder with the outer ends of the support arms beyond the cylinder in the same direction as the piston extends;

the erected position being with said part of the piston drawn into the cylinder and the support arms spread wide, with the plane formed by the outer ends of the support arms being beyond the forward end of the piston;

said operating lever in the closed position lying forward along the piston, and in the erected position lying back along the cylinder, being moved substantially 180° in operation from one position to the other;

support means comprising a bipod with a curved insert finger at its apex which is inserted into an opening in the rear end of the cylinder;

and a ball-stopping member which is attached to the outer ends of the support arms in the erected position.

4. A backstop device according to claim 3, wherein said ball-stopping member is a corded net which is attached by loops located on the peripheral binding of the net to net hooks on said outer ends of said support arms; there being four of said arms.

5. A backstop device according to claim 4, wherein near their outer ends said support arms are curved forward in the erected position, and said bipod is of a height

which brings the net surface to a generally vertical position.

6. A portable collapsible backstop device comprising a first and a second member adapted to slide one in the other along a common axis, a plurality of support arms and means hinging them to said first member, a plurality of arm braces and means hinging each at one end to said second member and at the other end to one of the support arms, an operating lever and means hinging it to the first member, a toggle lever and means hinging it at one end to the operating lever and at the other end to the second member;

so constructed and arranged that the operating lever is adapted for manual operation to move the toggle lever which moves the second member relative to the first member, which in turn moves the arm braces and support arms between an inactive closed position and an open erect position;

the closed position being with the first and second members extended relative to each other, the erected position being with the first and second members drawn partly together and the support arms spread wide;

support means attached in the erected position to the rear end of the cylinder;

and a ball-stopping member comprising a net which is attached by loops located on the peripheral winding of the net to net hooks on the outer ends of said support arms.

7. A portable collapsible backstop device comprising a first and a second member adapted to slide one in the other along a common axis, a plurality of support arms and means hinging them to said first member, a plurality of arm braces and means hinging each at one end to said second member and at the other end to one of the support arms, an operating lever and means hinging it to the first member, a toggle lever and means hinging it at one end to the operating lever and at the other end to the second member;

so constructed and arranged that the operating lever is adapted for manual operation to move the toggle lever which moves the second member relative to the first member, which in turn moves the arm braces and support arms between an inactive closed position and an open erect position;

the closed position being with the first and second members extended relative to each other;

the erected position being with the first and second members drawn partly together and the support arms spread wide, with the plane formed by the outer ends of the support arms being beyond the forward end of the second member, at least two of the support arms being used as the forward support of the backstop;

support means comprising a device having at least one leg and means attaching it to the rear end of said first member in the erected position to form the rear support of the backstop;

and a ball-stopping member comprising a net which is attached to the outer ends of the support arms in the erected position.
